US00D987936S

(12) **United States Design Patent** (10) Patent No.: **US D987,936 S**
(45) Date of Patent: **** Jun. 6, 2023**

(54) **SHORTS**

- (71) Applicant: **DashAmerica, Inc.**, Louisville, CO (US)
- (72) Inventors: **Lynn Bush**, Louisville, CO (US); **Alexander Strouthopoulos**, Louisville, CO (US); **Sarah App**, Louisville, CO (US)
- (73) Assignee: **SHOCK DOCTOR, INC.**, Fountain Valley, CA (US)
- (**) Term: **15 Years**
- (21) Appl. No.: **29/772,348**
- (22) Filed: **Mar. 1, 2021**

Related U.S. Application Data

- (62) Division of application No. 29/710,790, filed on Oct. 25, 2019, now Pat. No. Des. 914,329.

(57) **CLAIM**

The ornamental design for shorts, as shown and described.

DESCRIPTION

FIG. 1 is a perspective view of a pair of shorts showing our new design;

FIG. 2 is a front elevational view thereof;

FIG. 3 is a rear elevational view thereof;

FIG. 4 is a right side elevational view, the left side elevational view being a mirror image thereof; and,

FIG. 5 is a front elevational view of the present invention with a portion of the front of the shorts cut away and a portion of inner layer of the back cut away.

The broken lines shown in the figures are for the purpose of illustrating portions of the present invention that form no part of the claimed design.

1 Claim, 5 Drawing Sheets
